ALFRED L. ELLIOT, OF BOSTON, MASSACHUSETTS.

Design No. 4,383, dated October 4, 1870.

DESIGN FOR A COLLAR-BOX.

The Schedule referred to in these Letters Patent and making part of the same.

I, ALFRED L. ELLIOT, or Boston, in the county of Suffolk and State of Massachusetts, have invented a certain new and original Design for Collar-Box, of which the following is a specification.

The nature of my design is fully shown in the drawing; and

It consists in a collar-box, made in imitation of a valise, the two halves being hinged at the back as a valise, and supplied with handles and lock.

In the drawing—

A A are the halves or sides of the box, which are hinged at B, and supplied with handles C C.

The halves A are held together when closed by a lock or catch, d.

The style of finish may be varied, of course, to meet the taste of the maker, but the same general form and shape, that is, of a valise, would be preserved.

This collar-box makes an attractive feature in the sale of the goods for which it is intended.

I claim—

The design for a collar-box, in the form and style of a valise, substantially as set forth.

In testimony whereof, I have signed my name to this specification in the presence of two subscribing witnesses.

ALFRED L. ELLIOT.
